UNITED STATES PATENT OFFICE

161,606

BOTTLE CARRIER

Homer W. Forrer, Atlanta, Ga., assignor to Atlanta Paper Company, a corporation of Georgia

Application June 26, 1948, Serial No. 147,222

Term of patent 14 years

(Cl. D58—5)

To all whom it may concern:

Be it known that I, Homer W. Forrer, a citizen of the United States, residing at Atlanta, in the county of Fulton and State of Georgia, have invented a new, original, and ornamental Design for a Bottle Carrier, of which the following is a specification, reference being had to the accompanying drawing, forming part thereof.

I claim:

The ornamental design for a bottle carrier, as shown.

HOMER W. FORRER.
